SPANNER WRENCH WITH MEANS TO GRIP
THE INNER SURFACE OF PULLEY RIMS

Jerry J. Sullivan, Huntington Park, Calif.

Application May 31, 1946, Serial No. 673,308

5 Claims. (Cl. 81—90)

1

This invention relates to a spanner wrench which is particularly adapted for adjusting the valves of injectors of a Diesel engine, but may be used as a general purpose wrench.

One object of the invention is to provide a spanner wrench, so formed that it may be applied to a pulley wheel or the like and then caused to have binding grip with the inner surface of the rim of the wheel and turn the wheel when transverse swinging movement is imparted to the wrench.

Another object of the invention is to provide a wrench having a body formed with a head and a shank extending therefrom and carrying a handle which is pivotally mounted and disposed along a handle at the rear end of the shank, the head having depending lugs or teeth spaced from each other and the pivoted handle being connected with a bar or strip extending longitudinally of the shank, so that when the handles are grasped and the pivoted handle swung towards the rigid handle, a tooth or finger at the front end of the strip will shift into engagement with the rim of the pulley and together with the teeth of the head firmly grip the pulley and turn the pulley.

Another object of the invention is to provide a wrench wherein grip upon the pivoted handle which is naturally increased by strain exerted to turn the pulley will cause the teeth to be brought into firmer biting engagement with the rim of the pulley and thus prevent the teeth from slipping and moving about the pulley circumferentially thereof instead of turning the pulley.

Another object of the invention is to provide a wrench consisting of a few number of parts which are of simple construction and quite strong.

The invention is illustrated in the accompanying drawings wherein:

Figure 1 is an atop view of the improved wrench;

Figure 2 is a view showing the wrench partially in longitudinal section and partially in side elevation;

Figure 3 is a transverse sectional view taken along line 3—3 of Figure 1;

Figure 4 is a sectional view taken along line 4—4 of Figure 1;

Figure 5 is a view of the body portion of the wrench, and

Figure 6 is a side view of the bar or strip actuated by the pivoted handle of the wrench.

This spanner wrench has a body or main section 1 formed of steel or other strong metal and

2

shaped to provide a head 2, from which extends a shank 3 terminating in a rigid handle 4 having opposite faces formed with recesses 5. Through the head 2 is formed an opening 6 which flares towards its opposite ends and in front of this opening the head has its outer face formed with a recess 7 of triangular outline.

Lugs 8 extend downwardly from the head at opposite sides of the recess 7 and these lugs extend radially of the opening 6 and gradually increase in depth towards their outer ends which are beveled or tapered from opposite sides to form sharp ends for the lugs. The lugs constitute teeth for the head 2 and when the wrench is applied to a pulley wheel 9 with its outer or front end resting upon the rim 10 thereof, the sharp outer ends of the lugs or teeth will bear against the inner surface of the rim in spaced relation to each other circumferentially of the pulley.

An opening 11 is formed midway the width of the body 1, at approximately the junction of the head 2 with the shank 3 and through this opening passes a tooth or finger 12 formed by bending the front end of a metal bar or strip 13 which extends longitudinally of the shank and is seated in a recess 14 formed in the outer side face of the shank. An arcuate slot 15 is formed longitudinally of the shank adjacent the rear end of the recess 14 and through this slot passes a pin 16 which also passes through an opening 17 formed through the rear end portion of the strip or bar 13.

The pin 16 also extends through the openings 18 which are formed in the enlarged forward end portions 19 of the side walls 20 of a movable handle 21. This handle is U-shaped in cross section and straddles the shank of the handle 4, a pin 22 being passed through openings 23 formed in the handle 21 and through an opening 22 formed in the shank 3 to pivotally mount the handle 21 and permit it to have swinging movement towards and away from the rigid handle 4.

When the pivoted handle is swung away from the rigid handle, the bar 13 will be shifted forwardly and the teeth 8 and finger 12 may be fitted into the side recess of the pulley wheel 9 with the shaft 25 passing through the center opening 6 of the head 2. The two handles will then be grasped and pressure applied to swing the handle 21 towards handle 4 and the bar 13 will be drawn rearwardly and its finger brought into engagement with the inner surface of the flange of the pulley. This will cause the sharpened outer ends of the teeth 8 to bite into the

flange of the pulley and firmly grip it so that when the wrench is swung circumferentially of the shaft, the pulley and the shaft will be turned.

When force is exerted to turn the pulley, the gripping pressure upon the handles is increased and this will increase grip of the teeth upon the pulley. Therefore, the teeth will not slip circumferentially of the pulley and allow the wrench to be moved without turning the pulley. After the pulley has been turned as much as desired it is merely necessary to release grip upon the handles and the wrench may be readily removed from the pulley.

It will thus be seen from the foregoing description that I have provided a spanner wrench that will at all times be positive and efficient in its operation and further can be manufactured at a very low cost.

While I have shown the preferred embodiment of my invention, it is to be understood that various changes may be made in the size, shape and arrangement of parts without departing from the spirit of the invention and scope of the appended claims.

Having thus described the invention, what is claimed is:

1. A wrench comprising a body having a head at its front end and a shank extending rearwardly from the head and terminating in a rigid handle, the head being formed with an opening and the shank with a longitudinally extending recess, there being an opening formed adjacent the front end of the recess and a longitudinally extending arcuate slot near its rear end, said shank being formed near its rear end with an opening spaced transversely from the arcuate slot, lugs extending downwardly from the head forwardly of its opening and extending radially thereof and having their front ends beveled from opposite side faces to form sharpened front ends for the lugs, a movable handle U-shaped in cross section straddling the shank and the rigid handle and having front ends of its side flanges enlarged, a pin passing through the opening at the rear end of the shank and through side portions of the enlarged front end portion of the movable handle and pivotally mounting the movable handle, a strip extending longitudinally in the recess of the shank and having its front end portion bent to form a finger passing through the opening at the front end of the shank, the rear end of said strip fitting under the enlarged front end portion of one flange of the pivoted handle, and a pin passing through the slot of the shank and through aligned openings formed through the rear end of the strip and side portions of the front ends of the flanges of the pivoted handle to pivotally connect the strip with the pivoted handle and cause the strip to be shifted longitudinally and its tooth moved towards and away from the lugs when the pivoted handle is moved.

2. A wrench comprising a body having a handle at its rear end, a shaft-receiving opening being formed near the front end of the body, the intermediate portion of the body being formed with a forward opening and adjacent its rear end with a longitudinally extending slot, lugs extending downwardly from the body and forwardly from the shaft-receiving opening radially thereof and sharpened at their front ends and constituting teeth for engaging the inner surface of a marginal flange of a pulley carried by a shaft about which the wrench is fitted, a handle pivoted to the body in straddling relation thereto for swinging move-

ment transversely of the body, a strip extending longitudinally of the body and having its front end bent to form a finger passing through the forward opening, and a pin passing through the slot of the body and through aligned openings in the pivoted handle and the rear end of the strip to pivotally connect the strip with the pivoted handle and cause the strip to be shifted longitudinally and its finger moved towards and away from the lugs when the pivoted handle is moved transversely.

3. A wrench comprising an elongated body having its forward portion formed with a shaft-receiving opening, there being a finger-receiving opening spaced rearwardly from the shaft-receiving opening, lugs carried by the body and extending forwardly from the shaft-receiving opening radially thereof, a strip extending longitudinally of said body and having a finger at its front end passing through the finger-receiving opening for engaging a pulley and forcing the lugs into gripping engagement with the pulley when the strip is shifted longitudinally rearwardly of the body, a rigid handle at the rear end of the body, a movable handle straddling the body transversely thereof and pivoted at a side of its front end for swinging movement transversely of the body towards and away from the same, and a pin pivotally connecting the rear end of said strip with the pivoted handle and causing the strip to be shifted longitudinally when the pivoted handle is moved and shift the finger towards and away from the lugs.

4. A wrench comprising an elongated body having a rigid handle at its rear end, lugs projecting from a side face of the front end portion of said body and diverging forwardly and sharpened at their front ends, a strip extending longitudinally of said body and having a finger at its front end passing through an opening formed in the body rearwardly of the lugs, and a movable handle extending longitudinally of the body at a side of the rigid handle and having its front end portion straddling the body and pivoted thereto and pivotally connected with the rear end of the strip for shifting the strip and its finger longitudinally of the body when the pivoted handle is swung towards and away from the rigid handle.

5. A wrench comprising an elongated body having a rigid handle at its rear end, wheel-engaging teeth spaced from each other transversely of the front end of the body, the body being formed with an opening spaced rearwardly from said teeth, a strip extending longitudinally of said body and having a wheel-engaging finger at its front and passing through the opening, and a movable handle extending longitudinally of the body at one side of the rigid handle and having its front end portion pivoted to the body and pivotally connected with the rear end of said strip for shifting the strip longitudinally when the pivoted handle is moved towards and away from the rigid handle.
